DESIGN FOR A LAMP BRACKET

Otto G. Hildebrand, Cleveland, Ohio

Application February 21, 1933. Serial No. 47,281

Term of patent 7 years

To all whom it may concern:

Be it known that I, OTTO G. HILDEBRAND, a citizen of the United States, residing at Cleveland, in the county of Cuyahoga and State of Ohio, have invented a new, original, and ornamental Design for Lamp Bracket, of which the following is a specification, reference being had to the ac-

companying drawing, forming part thereof, wherein Fig. 1 is a side elevation and Fig. 2 an end elevation of such bracket.

I claim:

The ornamental design for a lamp bracket substantially as shown.

OTTO G. HILDEBRAND.
